POCKET ATOMIZER

Rome C. Seyforth, Shelby, Ohio, assignor to The
Shelby Metal Products Company, Shelby, Ohio,
a corporation of Ohio

Application November 29, 1935, Serial No. 52,118

7 Claims. (Cl. 299—88)

The present invention relates to a pocket atomizer for spraying perfumes or similar toilet liquids.

An object of the invention is to provide an atomizer of simple and economical construction wherein complicated parts such as check valves, operating latches, and other similar mechanism which heretofore has added to the expense of manufacture and to the convenience of operation, are eliminated.

Another object of the invention is to provide an atomizer construction wherein the movable element is substantially enclosed and protected by the outer casing, and wherein the movable element which is operable to effect air compression and spraying action, is normally maintained in a position at the beginning of its air compression and spraying stroke, whereby the atomizer is always immediately ready to produce a spraying action without further manipulation or movement.

Another object of the invention is to provide novel means for sealing the liquid containing reservoir when the atomizer is not in operation in order to prevent any leakage or loss of liquid.

Still another object of the invention is to provide means for properly aligning the parts which move with respect to each other both during movement, and while they are at rest.

Additional objects and advantages of the invention shall become apparent as the following description proceeds.

To the accomplishment of the foregoing and related ends, said invention, then, consists of the means hereinafter fully described and particularly pointed out in the claims.

The annexed drawing and the following description set forth in detail certain structure embodying the invention, such disclosed means constituting, however, but one of various structural forms in which the principle of the invention may be used.

In said annexed drawing:

Fig. 1 is an elevational view of the exterior of the atomizer embodying the principle of the invention; Fig. 2 is an elevational view taken upon a plane normal to that of Fig. 1; and Fig. 3 is a view of the upper exterior end of the atomizer; Fig. 4 is an elevational view in section; Fig. 5 is a detailed, partially sectioned view of the combined air compressing plunger and liquid container; and Fig. 6 is a sectional view taken upon a plane normal to that of Fig. 4 and substantially along line 6—6 thereof.

Now referring more particularly to the draw-

ing, there is shown therein an outer cylindrical casing 1, in which a combined air compressing and liquid containing member 2 is movably mounted. The member 2 is of a cylindrical contour in order to conform with the interior of the outer casing 1 and can be fabricated from a molded, non-metallic material such as bakelite or a similar plastic compound, or from metallic material such as a die cast white metal. The lower end of the casing 1 is closed by means of a flanged end wall 3 which threadably engages the casing 1 as indicated at 4. An air compression chamber 5 is thus defined in the lower end of the casing 1 by the bottom end of the member 2 and the bottom wall 3. A compression spring 6 is located in the air compression chamber 5, bears against the bottom 3 of the casing 1 and the bottom of the member 2, and urges the latter in an upward position which is limited by the top end 7 of the casing 1. The side and end walls of the casing 1 are partially removed as indicated at 8 whereby a portion of the member 2 is exposed. Thus the upper end 9 of the member 2 is not surrounded and enclosed by the casing 1 whereby it serves as a bearing surface for the contact of the operator's finger or thumb.

The interior of the member 2 is hollow and defines a liquid containing reservoir 10. A filler plug 11 threadably engages the wall of the member 2 and extends through the elongated slot 12 in the wall of the casing 1. The elongated slot 12, together with the filler plug 11, serves as means for guiding and aligning the member 2 when it is moved with respect to the casing 1. A liquid conduit tube 13 extends into the interior 35 of the liquid reservoir 10 and terminates exteriorly of the member 2 as at 14. An air vent conduit 15 communicates with the upper end of the liquid reservoir 10. Both the upper end 16 of the air vent 15 and the upper end 14 of the liquid conduit 13 are located in substantially the same plane and are adapted to bear against a resilient pad 17 located in the end 7 of the casing 1 when the atomizer parts are in normal position. The resilient pad 17 is composed of material such as rubber; thus it serves as a means for sealing both the liquid and air conduits extending into the interior of the liquid reservoir 10. The pad 17 is secured in the end 7 of the casing 1 by means of an inwardly extending flange 18. The flange 18 is slightly inclined towards the pad 17 whereby the latter is compressed and thereby securely held in position.

A shoulder or transverse face 19 is formed on the member 2 and adapted to bear against and

coact with the flange 18, whereby the member 2 is aligned and locked against rotation with respect to the casing 1 when the parts are in normal position. In this manner, when the filler plug 11 is removed, the member 2 will be held in proper position with respect to the casing 1 and the filler plug opening cannot thereby be inadvertently rotated to a position where it would be obscured or partially covered by the 10 wall of the casing 1.

A tubular air conduit 20 is positioned centrally of the member 2. Its upper end is retained in an annular boss 21 extending inwardly from the top wall 9 of the member 2. A minute air passage 15 22 extends from the upper end of the air conduit 20 to a point in alignment with the upper end 14 of the liquid conduit 13. The lower end of the air conduit 20 extends below the bottom of the member 2 and through the bottom wall 23 thereof. 20 The bottom wall 23 of the member 2 tightly fits in a groove as at 24. A compressible washer 26, composed of rubber or the like, tightly fits against the inner wall of the member 2, and effectively seals the interior thereof. A threaded nut 25 engages over the lower end of the air conduit 20 and secures a washer 26 and a flexible sealing gasket 27 to the lower end of the member 2. The sealing gasket 27 serves as means for slidably sealing the member 2 to the inner wall of the casing 1, thus forming in effect a piston or plunger adapted to operate in the air compression chamber 5.

The operation of the device is as follows: Liquid perfume or similar toilet preparation is introduced into the reservoir 10 by means of removing the filler plug 11. The atomizer is then ready for immediate use and operation. The operator grasps the upper end 9 of the member 2 and the bottom wall 3 of the casing 1 between the thumb and index or fore finger and thereby forces the member 2 downwardly, whereupon air will be forced from the chamber 5 up through the tube 20 through the passage 22 and across the top of the liquid conduit 13. Such a passage of air across the top of the liquid conduit 13 produces an aspirator or suction effect which draws liquid up through the latter tube from the reservoir 10 and ejects it in the form of a spray out through the elongated slot 12. Upon release of pressure, the spring 16 returns the parts to their original position as shown in Fig. 4 and seals the upper ends 14 and 16 of the liquid conduit 13 and air vent 15 respectively against the face of the resilient pad 17. The air vent 15 permits the introduction of atmospheric pressure to the liquid reservoir 10 so that removal of liquid therefrom will not produce a vacuum which might prevent the passage of liquid up through the conduit 13. It should also be noted that the spray emanating 60 from the opening 22 moves from the top to the bottom of the downward stroke of the member 2 whereby an effective distributing effect is obtained.

It will thus be seen that a pocket atomizer embodying the principle of the foregoing described invention possesses the advantages of extremely simple and economical construction, wherein the operation of the movable parts is encompassed entirely within the limits of the outer casing. 70 Furthermore, the atomizer is at all times immediately ready for operation and does not necessitate the manipulation of any locks, levers, or catches in order to free the movement of the parts or to effect an opening of the various air or liquid conduits. The atomizer can be operated

easily with one hand and after operation immediately returned to a pocket or purse without the bother of closing a cover, catch, or valve, or locking a plunger. It should also be noted that since the combined liquid containing and air 5 compressing member 2 is normally in an outward position with respect to the air chamber 5, that the compression spring 6 is also normally in an expanded position. In this manner, the life of the compression spring is greatly increased, since 10 it is subjected to full compression only when the atomizer is in operation.

Other modes of applying the principle of my invention may be employed instead of the one explained, change being made as regards the structure herein disclosed, provided the means stated by any of the following claims or the equivalent of such stated means be employed.

I therefore particularly point out and distinctly claim as my invention:

1. In an atomizer, the combination of a rigid casing having top, bottom, and side wall portions, a liquid containing member movable in said casing as a plunger to compress an air supply therein, atomizing means connected to such air supply 25 and carried by said member for spraying liquid from said member to the exterior of said casing, and an opening in said casing to give access to said member for the actuation thereof.

2. In an atomizer, the combination of a rigid 30 casing having top, bottom, and side wall portions, a liquid containing member movable in said casing as a plunger to compress an air supply therein, atomizing means connected to such air supply 35 and carried by said member for spraying liquid from said member to the exterior of said casing, an opening in said casing to give access to said member for the actuation thereof, and a filler opening in said member, said casing having an opening in registry with said filler opening.

3. In an atomizer, the combination of a rigid 45 casing having top, bottom, and side wall portions, a liquid containing member movable in said casing as a plunger to compress an air supply therein, atomizing means connected to such air supply 45 and carried by said member for spraying liquid from said member to the exterior of said casing, an opening in said casing to give access to said member for the actuation thereof, a filler 50 opening in said member, a closure plug for said opening, and an elongated slot in said casing for the extension of said plug.

4. In an atomizer, the combination of a rigid 55 casing having top, bottom, and side wall portions, a liquid containing member movable in said casing as a plunger to compress an air supply therein, atomizing means connected to such air supply 60 and carried by said member for spraying liquid from said member to the exterior of said casing, an opening in said casing to give access to said member for the actuation thereof, and a shoulder on the end of said member adapted to fit against a complementary shoulder on said casing when said member is in inoperative position.

5. In an atomizer, the combination of a rigid 70 casing having top, bottom, and side wall portions, a liquid containing member movable in said casing as a plunger to compress an air supply therein, atomizing means connected to such air supply 75 and carried by said member for spraying liquid from said member to the exterior of said casing, an opening in said casing to give access to said member for the actuation thereof, said

- atomizing means including a liquid conduit extending from the interior of said member and having its outer end terminating at a point adjacent the end of said member, and a resilient pad mounted in said casing for closing said outer conduit and when said member is in inoperative position.
6. In an atomizer, the combination of a rigid casing having top, bottom, and side wall portions, a liquid containing member movable in said casing as a plunger to compress an air supply therein, atomizing means connected to such air supply and carried by said member for spraying liquid from said member to the exterior of said casing, an opening in said casing to give access to said member for the actuation thereof, said atomizing means including a liquid conduit extending from the interior of said member and having its outer end terminating at a point adjacent the end of said member, an air vent adjacent said outer conduit and leading to the interior of said member, and a resilient pad mounted in said casing for closing said outer conduit
- 10
- 15
- 20

end and said air vent when said member is in inoperative position.

7. In an atomizer, the combination of a rigid casing having top, bottom, and side wall portions, a liquid containing member movable in said casing as a plunger to compress an air supply therein, atomizing means connected to such air supply and carried by said member for spraying liquid from said member to the exterior of said casing, an opening in said casing to give access to said member for the actuation thereof, said atomizing means including a liquid conduit extending from the interior of said member and having its outer end terminating at a point adjacent the end of said member, an air vent adjacent said outer conduit and leading to the interior of said member, a resilient pad mounted in said casing for closing said outer conduit end and said air vent when said member is in inoperative position, and an inwardly extending flange on said casing and bearing against said resilient pad for securing the latter in position.
